UNITED STATES PATENT OFFICE.

ANTOINE BÉNASSY, OF GENEVA, SWITZERLAND.

SWITCH.

No. 799,135.

Specification of Letters Patent.

Patented Sept. 12, 1905.

Application filed December 17, 1904. Serial No. 237,200.

To all whom it may concern:

Be it known that I, ANTOINE BÉNASSY, manufacturer, of Geneva, Switzerland, have invented certain new and useful Improvements 5 in and Relating to Switches, of which the following is a specification.

My invention relates to improvements in electric switches; and the object of my invention is to provide a switch for electric circuits, as the lighting-circuit of motor-cars, which shall be simple in construction and efficient in operation and which shall embody means that prevent tampering with the mechanism.

15 In the drawings illustrating the principle of my invention and the best mode now known to me of applying that principle, Figure 1 is a front view of the base-board of the switch. Fig. 2 is a central sectional view through my 20 new switch, the circuit being shown as interrupted. Fig. 3 is a detail view showing the base of the cap, the parts being in the position shown in Fig. 2. Fig. 4 is a detail view showing the interior of the locking-cover. 25 Figs. 5 and 6 show forms of keys, and Fig. 7 is a transverse section of the keys shown in Figs. 5 and 6 and is the same for both forms of key.

The base-board *a*, Fig. 1, is made of insulating material and is provided with circuit-terminals *b* and *c*, the gap between which may be bridged by a lever *d*, pivoted upon the terminal *b* and controlled by a spring *d'*, which tends by its tension to force the free 35 end of the lever *d* into contact with the terminal *c*, and thereby to make the circuit.

Upon the base *a* is mounted a cap *e*, in which is slidably fitted a bolt *f*, the lower end of which is controlled by a spring *i*, that 40 tends to force bolt *f* upwardly out of the cap *e*. (See Figs. 2 and 4.) The bolt *f* is stepped, as best shown in Fig. 2, and the spring-blades *h*, mounted in the cap-cover *g*, Fig. 4, are adapted to engage in the steps or 45 notches *f'* *f''* of the bolt *f* to retain the latter in the positions determined by the steps *f'* *f''*. In Fig. 2 the blades *h* are shown in engagement with the step or notch *f''*. The cap-cover *g* is secured to the cap *e* in the following manner: Projecting from the inside 50 of the cap-cover *g* are two tenons *k* *k'*, both of which are circumferentially grooved, as indicated by the dotted lines in Fig. 4. The base of the cap *e* is formed with two keyhole-shaped slots *l* *l'*, which are slightly curved and which are adapted to coöperate with the

tenons *k* *k'*, respectively. The tenons are passed through the larger end of the slots *l* *l'* and the cap-cover *g* is then turned slightly, so as to bring the reduced portions of the tenons 60 *k* *k'* into the narrow portion of the slots *l* *l'*. The spring-blades are then engaged in one of the steps *f'* *f''* by forcing down the bolt *f* the proper distance. Thus the cap-cover *g* is locked in place upon the cap *e*. 65

To release the bolt *f* from the blades *h* and the cap-cover *g* from the cap *e* the following provision is made: As shown in Fig. 3, the face of the bolt *f* is fluted or corrugated and is provided with flanges *f'''*, which project out 70 beyond the ridges of the fluted surface. The inside of the cap-cover *g* is also fluted, as shown at *g'*, Fig. 4. The flanges *f'''* maintain the cap-cover *g* at a distance from the face of the bolt *f* such that a keyway exists between the two members *f* and *g* suitable for the passage of one or the other of the fluted 75 keys *m* *m'*. (Shown in transverse section in Fig. 7 and in elevation in Figs. 5 and 6.) The ridges and grooves formed on these keys 80 are of course adapted to fit the ridges and grooves of the keyway formed between the bolt *f* and the cap-cover *g*. The key *m'* is longer than the key *m*, the latter being of only sufficient length to reach the step *f''* and 85 to disengage the blades *h* therefrom, while the key *m* is of sufficient length to disengage the blades *h* from either the step *f''* or from the step *f'*.

By means of the key *m* the blades *h* are disengaged from the step *f''*, thereby permitting the spring *i*, Figs. 2 and 4, to force the bolt *f* up until the step *f'* engages the blades *h*. In this position the cap-cover *g* is still locked upon the cap *e*, for obviously the blades *h* 95 prevent the rotation of the cap-cover *g* when they are engaged with either of the steps *f'* *f''*. By using the key *m'* the blades *h* may be disengaged from both steps of the bolt *f*, thereby allowing the bolt *f* to be withdrawn 100 and the cap-cover *g* turned for purpose of removal. When the key *m* is used and the blades *h* pass from engagement with the step *f''* to engagement with the step *f'*, as above described, the lever *d* contacts with the terminal *c* and makes or completes the circuit. 105

What I claim is—

1. The combination in an electric switch of a base provided with terminal posts; a lever mounted on said base for bridging the gap 110 between said terminal posts; a cap mounted on said base; a bolt adapted to control said

lever, said bolt being slidably mounted in said cap; means for locking said bolt in position; and a releasing device for said means.

2. The combination in an electric switch of a base provided with terminal posts; a lever mounted on said base for bridging the gap between said terminal posts; a cap mounted on said base; a notched bolt mounted in said cap and adapted to control the position of said lever; and a cap-cover provided with spring-blades for engaging said notched bolt to maintain it in position.

3. The combination in an electric switch of a base provided with terminal posts; a lever mounted on said base for bridging the gap between said terminal posts; a cap mounted on said base; a notched bolt mounted in said cap and adapted to control the position of said lever; a cap-cover detachably secured to said cap and provided with spring-blades for engaging said notched bolt to maintain it in position; and means for releasing said bolt from said spring-blades.

4. The combination in an electric switch of a base provided with terminals; a make-and-

break device mounted upon said base; a device which shields said make-and-break device and interlocks therewith and with said base; and means for releasing said devices from each other.

30

5. The combination in an electric switch, of a base provided with terminals; a make-and-break device mounted on said base; a cover for said make-and-break device; and means for interlocking said cover and device.

35

6. In combination in an electric switch, a base provided with terminals; a make-and-break device mounted on said base; a cover for said make-and-break device; means for interlocking said cover and device; and means 40 for controlling said make-and-break device and disengaging said cover therefrom.

In testimony whereof I have signed my name to this specification in the presence of two subscribing witnesses.

ANTOINE BÉNASSY. [L. S.]
